STRUCTURAL ELEMENT

Hugh L. Waugh, Ferndale, Mich., assignor to
Stran-Steel Corporation, Detroit, Mich., a cor-
poration of Michigan

Application December 18, 1933, Serial No. 703,001

6 Claims. (Cl. 189—37)

The invention relates to structural elements and refers more particularly to structural elements, such as joists, studs and the like employed in buildings.

One of the objects of the invention is to provide an improved structural element having a bearing face for covering material equivalent to that provided by a corresponding wooden element and arranged to receive nails or equivalent securing means spaced transversely thereof for securing the covering material thereto, whereby the adjacent ends of different members forming the covering material may be individually supported upon and effectively secured to the structural element. Another object is to so construct the structural element that its parts may be readily and economically secured together. A further object is to form the structural element of metal and to so arrange and construct the parts thereof that the structural element is relatively light in weight.

These and other objects of the invention will become apparent from the following description, taken in connection with the accompanying drawings, in which

Figure 1 is a side elevation of a portion of a structural element showing an embodiment of my invention;

Figure 2 is a cross section on the line 2—2 of Figure 1;

Figures 3, 4, 5, 6 and 7 are views similar to Figure 2 showing other embodiments of my invention;

Figure 8 is a side elevation of the embodiment shown in Figure 6;

Figure 9 is a side elevation of the embodiment shown in Figure 7.

The structural element shown in Figures 1 and 2 may be used as a joist, stud, rafter, or like element, in a building, such as a residence. This structural element comprises the pair of metallic flanged members 1 and 2 which, as shown, are channel members having the pairs of co-planar flanges 3 and 4 respectively at their edges and the webs 5 and 6 respectively extending between the inner edges of these flanges and having their central portions substantially parallel and spaced from each other. The corresponding portions of the webs adjacent each pair of co-planar flanges have the longitudinal transversely curved corrugations 7 and 8 respectively which converge from the co-planar flanges to the central web portions. 9 are metallic intermediate members between the pairs of co-planar flanges 3 and 4 and the corrugations 7 and 8. Each intermediate

member, as shown, is formed of the same gauge sheet metal as the channel member and has the outer wall 10 which is substantially in the same plane as the co-planar flanges 3 and 4 and the side walls 11 and 12 extending inwardly from the outer wall 10 between the corrugated portions 7 and 8 and converging toward each other. These side walls have longitudinal transversely curved corrugations which are complementary to the adjacent corrugations 7 and 8 and are substantially uniformly spaced therefrom to form spaced curved slots for receiving the fastening elements, such as the nails or equivalent securing means 13 for securing the members 14 and 15 forming part of the covering material against the bearing faces formed by the co-planar flanges 3 and 4, the adjacent edges of these members preferably abutting at or near the median plane of the intermediate member. The widths of the slots or the spacing, the curvature of the slots, and the rigidity of the portions of the channel members and intermediate member forming the walls of these slots are such that the fastening elements are caused to bend and thereby be clinched to the structural element and effectively held in position when driven in between the channel members and intermediate member transversely thereof.

The channel members and intermediate members are rigidly secured together and, as shown in the present instance, the central portions of the channel members are provided inwardly of and adjacent the corrugations 7 and 8 with the bosses 16 spaced longitudinally thereof and abutting the inner edge portions of the side walls 11 and 12 of each intermediate member. Suitable securing means, such as the rivets 17, extend through these bosses and the inner edge portions and rigidly hold the parts in assembled relation.

With this construction, it will be seen that the co-planar flanges 3 and 4 and the outer wall 10 of the intermediate member form bearing faces for individually supporting adjacent members forming part of the covering material and extending transversely of the structural element. It will also be seen that the parts forming the structural element may be readily and effectively secured together.

In the modification shown in Figure 3, the metallic structural element comprises the pairs of flange members 18 and 19 which are in the nature of angle irons. Each pair of angle irons has the co-planar flanges 20 and the flanges 21 extending from the inner edges of the co-planar flanges toward the other pair of angle irons. The

last mentioned flanges have longitudinal transversely curved corrugations which are complementary. 22 is the web member which in the present instance forms the intermediate member. This web member extends between the pairs of angle irons and has at its edges the longitudinal transversely curved corrugations 23 which are complementary to the corrugations of the angle irons. The edges of the web member terminate in substantially the planes of the outer faces of the flanges 20 and are preferably pointed. The corrugations 23 are spaced from the corrugated portions of the angle irons to form spaced curved slots to receive and retain the fastening elements in the same manner as the structure shown in Figures 1 and 2. The angle irons and the web member are preferably secured together by suitable securing means 24, such as rivets, which extend through the portions of the web member 22 adjacent the corrugations 23 and the bosses 25 at the inner edge portions of the flanges 21.

Figure 4 shows another modification in which 26 is the web member of the structural element and 27 and 28 are the flanged members at the edges of the web member. These flanged members are preferably in the nature of angle irons and have the co-planar flanges 29 and the flanges 30 extending from the inner edges of the co-planar flanges and converging toward each other. These flanges 30 have longitudinal transversely curved corrugations. 31 is the intermediate member similar to the intermediate member 9 of Figures 1 and 2, but having the inner edge portions 32 of its side walls spaced apart to receive the edges of the web member 26. The longitudinal transversely curved corrugations 33 of the side walls of the intermediate member are substantially uniformly spaced from the corrugations of the flanges 30 to form spaced curved slots for receiving and retaining the fastening elements. The inner edge portions of the flanges 30 are formed with the bosses 34 which contact with the inner edge portions 32 of the side walls of the intermediate member. Suitable securing means, such as the rivets 35, extend through these bosses, the inner edge portions of the side walls of the intermediate member, and the edge portion of the web member.

Figure 5 discloses another modification of structural element in which the intermediate member 36 is integral with the web member 37 and formed from the same metal sheet or plate. As shown, one of the side walls of the intermediate member connects integrally into the web member and the other side wall terminates adjacent the zone of connection of the first side wall of the web member. Also in this construction, the co-planar flanges 38 of the flanged members or angle irons terminate at their outer edges in the flanges 38' extending in the same general direction as the corrugated flanges, thereby additionally reinforcing the structural element. The inner edge portions of the flanges 39 of the flanged members are formed with the spacing bosses through which the securing means extends.

Figures 6 and 8 disclose a trussed type of structural element in which the web member is in the nature of the round rod 40 alternately connected to the upper and lower chords at longitudinally spaced points. Each of these chords is formed of the pair of flanged members 41 which are in the nature of angle irons formed in the same manner as the flanged members of Figure 4. The intermediate member 42 is preferably

formed of a metal sheet or plate of substantially the same gauge as the flanged members and has the outer wall 43 in the same plane as the co-planar flanges of the flanged members. The intermediate member also has the inwardly converging side walls 44 cooperating with the corrugated flanges of the flanged members to form the spaced curved slots for receiving and retaining the fastening elements. The web member or rod 40 zig zags between the pairs of flanged members and the bases of its U-shaped portions 45 extend between the inner edge portions of the side walls 44 and are suitably secured thereto as by welding. The flanged members may be suitably secured in assembled relation as by welding the bosses at the inner edge portions of the flanged members to the inner edge portion of the side walls 44.

Figures 7 and 9 disclose another construction of structural element in which the flanged members 46 are integral with or welded to the web member 47, the latter comprising the truss rods 48. The flanged members of each pair, as shown, are integral and they cooperate with the side walls of the intermediate member 49 to form rounded slots for receiving and retaining the fastening elements. This intermediate member is tubular and is suitably secured to the flanged members, for example, by providing the latter with bosses for engaging the side walls of the spacer and being secured thereto as by welding. The outer wall of each intermediate member in this construction is also substantially in the same plane as the co-planar flanges of the flanged members.

From the above description, it will be readily seen that I have provided an improved structural element which is adapted to support the adjacent ends of different members forming the covering material and to which these adjacent ends may be effectively secured. It will also be seen that the structural elements are formed of metal sheets or plates and the parts are so constructed and arranged that they may be readily and economically secured together and the structural elements may be of relatively light weight and of great strength.

What I claim as my invention is:

1. In a structural element, flanged members having substantially co-planar flanges and flanges extending in the same direction from the inner edges of said co-planar flanges and formed with longitudinal transversely curved corrugations, an intermediate member between said last mentioned flanges and having a portion substantially uniformly spaced from each to form laterally spaced curved slots to receive and retain fastening elements, and means inwardly of said corrugations for rigidly securing said flanged members and intermediate member in assembled relation.

2. In a metallic structural element, metallic angle members having substantially co-planar flanges and flanges extending in the same direction from the inner edges of said co-planar flanges, said last mentioned flanges having longitudinal transversely curved corrugations, and a metallic intermediate member between said last mentioned flanges and having a portion substantially uniformly spaced from each to form laterally spaced curved slots to receive and retain fastening elements and a portion extending between said last mentioned flanges inwardly of their corrugations, and means for securing said

last mentioned portion directly to said last mentioned flanges.

3. In a structural element, flanged members having substantially co-planar flanges and flanges extending in the same direction from the inner edges of said co-planar flanges and formed with longitudinal transversely curved corrugations, and an intermediate member between said last mentioned flanges and having spaced longitudinal transversely curved corrugations, the corrugations of said last mentioned flanges and intermediate member being complementary to form laterally spaced curved slots to receive and retain fastening elements, and means inwardly of said corrugations for securing said flanged members and intermediate member in assembled relation.

4. In a structural element, flanged members having substantially co-planar flanges and flanges extending from the inner edges of said co-planar flanges and converging toward each other and formed with longitudinal transversely curved corrugations, an intermediate member between said last mentioned flanges having an outer wall substantially co-planar with said co-planar flanges and side walls extending inwardly between said last mentioned flanges and converging toward each other, said side walls being substantially uniformly spaced from the corrugations of said last mentioned flanges to form spaced curved slots to receive and retain fastening elements, a web member extending between said side walls and means inwardly of said corrugations for securing said flanged members, intermediate member and web together.

5. In a structural element, flanged member

having substantially co-planar flanges and flanges extending from the inner edges of said co-planar flanges and converging toward each other and formed with longitudinal transversely curved corrugations, a hollow intermediate member between said last mentioned flanges and having an outer wall in substantially the plane of said co-planar flanges and side walls extending from said outer wall and converging toward each other, said side walls being substantially uniformly spaced from the corrugations of said last mentioned flanges to form spaced curved slots to receive and retain fastening elements, a web member bar extending between said side walls at points spaced longitudinally thereof, and means inwardly of said corrugations for securing said angle members, spacer and bar together.

6. In a structural element, flanged members having substantially co-planar flanges and flanges extending from the inner edges of said co-planar flanges and converging toward each other and formed with longitudinal transversely curved corrugations and an intermediate member between said last mentioned flanges and having an outer wall in substantially the plane of said co-planar flanges and side walls extending from said outer wall and converging toward each other and substantially uniformly spaced from the corrugations of said last mentioned flanges to form spaced curved slots to receive and retain fastening elements, a web member, and means inwardly of said slots for rigidly securing said web member and flanged members together.

HUGH L. WAUGH.
